CLAIM

The ornamental design for a room air conditioner housing comprised of the front, rear, top and side panels, as shown and described.

DESCRIPTION

FIG. 1 is a front elevational view of a room air conditioner housing comprised of the front, rear, top and side panels, showing our new design;

FIG. 2 is a top plan view thereof;

FIG. 3 is a right side elevational view thereof;

FIG. 4 is a left side elevational view thereof; and,

FIG. 5 is a rear elevational view thereof.

The broken line showing of a handle in FIGS. 1-5 is for illustrative purposes only and forms no part of the claimed design.

FIG. 1

FIG. 2

FIG. 3

FIG. 4

FIG. 5
